FASTENER FOR ATTACHING A BUTTON

Francis G. Merser, Framingham, Mass., assignor to
Dennison Manufacturing Company, Framingham,
Mass., a corporation of Nevada

Filed Feb. 19, 1968, Ser. No. 10,622

Term of patent 14 years

U.S. Cl. D2—423
Int. Cl. D2—08

Fig. 1

Fig. 2

Fig. 3

FIG. 1 is a top plan view of a fastener for attaching a button or the like showing my new design;

FIG. 2 is a side elevational view thereof; and

FIG. 3 is an end elevational view.

I claim:

The ornamental design for a fastener for attaching a button, substantially as shown.
